CLAIM

The ornamental design for a lever for terminal socket, as shown and described.

DESCRIPTION

FIG. 1 is a perspective view of a lever for terminal socket showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is second perspective view thereof;

FIG. 9 is third perspective view thereof; and,

FIG. 10 a perspective view showing the lever for terminal socket in use.

The broken lines in the drawings illustrate portions of the lever for terminal socket that form no part of the claimed design.
